SURGICAL INSTRUMENT

Samuel J. Blumenthal, Brooklyn, N. Y.

Application March 26, 1940, Serial No. 325,943

6 Claims. (Cl. 128—309)

This invention relates to surgical instruments designed primarily for use in the removal of tonsils or in performing what is commonly termed tonsillectomy by instruments termed tonsillotomes; and the object of the invention is to provide an instrument of the character described employing a comparatively thin tonsil receiving ring with two supporting or engaging blades having outer surfaces flush with the surfaces of the ring and with means for applying equalized pressure to both blades in firmly engaging the tissue intermediate the tonsil and throat and in supporting the tissue in a manner facilitating cutting thereof by a knife movably disposed between said blades; a further object being to provide an instrument of the character described wherein the outer extremity of the ring is provided centrally thereof with a recess receiving the pointed end only of a knife, and further in the provision of a pointed cutter edge on the knife to first puncture and then shear cut the tautly supported tissue, thereby simplifying the severing operation and insuring positive cutting of the entire tissue in removal of the tonsil; a still further object being to provide means for keying and coupling the several blades one with respect to the other to facilitate independent and collective movement of the blades including the knife and in utilizing said keying means as part of the means for moving the knife into the cutting or shearing position; and with these and other objects in view, the invention consists in an instrument of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a plan view of an instrument made according to my invention with part of the construction broken away.

Fig. 2 is a longitudinal sectional view on the line 2—2 of Fig. 1.

Fig. 3 is a view similar to Fig. 2 showing only a part of the construction with parts in a different position.

Figs. 4, 5 and 6 are views similar to Fig. 3 showing the parts in other positions; and

Fig. 7 is an exploded view of a part of one end portion of the instrument illustrating the several blade members in their related position.

My present invention forms a continuation in part of the structure disclosed in my prior application, Ser. No. 208,983, filed May 20, 1938. In the present application, certain features which were disclosed in said prior application are incorporated but modified to adapt the same to the new structural features of the present instrument.

In tonsillectomy, many difficulties have been experienced at the crucial moment, namely the moment of performing the severing operation of the tonsil, which results in the incomplete severance of the tonsil causing inconvenience and annoyance to the physician and sometimes serious trouble to the patient. In other instances, unnecessary injury to the throat tissue is experienced by reason of slippage of the tissue during the cutting operation or removal of the tonsil. Further, unnecessary injury to the tissue or pillars is experienced by using tonsillotomes having unnecessarily thick or heavy ring ends. It is the purpose of my invention to obviate these and other objectionable features to instruments of this type and kind, while at the same time producing an instrument which is substantially fool-proof in operation in the manipulation of the several blades including the cutter blade or knife, as will more fully hereinafter appear. Still further, it is an object of my invention to provide an instrument of the character described employing parts of simple and easily cleanable construction with the means for quickly and easily attaching and detaching the several parts for cleaning and sterilization.

In Figs. 1 and 2 of the drawing I have shown at 10 the elongated shank or body of the instrument which includes a protruding handle portion 11, only part of which is shown in Fig. 2 of the drawing. Above the handle portion, the body is yoke-shaped in form to provide upwardly extending side plates 12 having bayonet apertures 13 to receive the lock plate 14 pivoted to one of the plates 12 as seen at 15. The forward end of the body 10 terminates in what is commonly termed a ring 16 having a groove 17 extending from the outer end 18 of the ring along the sides of the rectangular blade guiding portion 19 disposed inwardly of said ring. The outer end 18 of the ring 16 is also apertured as seen at 20 centrally of said end and in alignment with the groove 17 to receive the pointed and sharpened end of the blade as will later appear. The blade guiding portion 19 of the body 10 is composed of a top plate 21, and the forward extension of the body 10 as at 22, and three blades

23, 24 and 25 are movably disposed between the parts 21 and 22 as will be apparent.

The blades 23 and 24 may be said to be tissue engaging blades, whereas the blade 25 may properly be termed the cutter blade or knife. This knife is disposed intermediate the blades 23 and 24. The body 10 has a rectangular extension 10a rearwardly of the handle 11 which terminates in a long threaded rod 26 preferably having what is termed a double thread to provide quick and free movement of a large knurled nut 27 longitudinally of the screw 26. At the end of this screw is a stop nut 28 limiting outward movement of the nut 27. In this way the nut 27 may be quickly and easily spun by the physician in moving the same into operative and inoperative positions, and is sufficiently large in diameter to exert the required pressure on the blades 23, 24 in applying equalized pressure thereto as later described.

The upper surface 10b of the body 10 is straight and smooth throughout the entire length thereof from the part 22 to the part 10a to provide free sliding movement of the blade 24 thereon and in like manner the free sliding movement of the other blades 25, 23 which are disposed upon the blade 24. All of the blades are of sufficient width adjacent the yoke-shaped portion defined by the plates 12 to be guided in their sliding movement by these plates. The outer end portions of the blades 23 and 24 are enlarged to fit snugly but freely in the hollow frame 19, whereas the blade or knife 25 is slightly wider than the blades 23 and 24 to be guided in the groove 17 where it extends along the sides of the frame 19.

The blade 23 is enlarged in thickness inwardly of the wide end thereof as seen at 23a. This thickened portion terminates at its inner end in a heavy yoke-shaped part 29 which fits over and is movable longitudinally of the screw 26. The blade 23 also has forwardly of the yoke 29 laterally extending wings 30 forming finger or thumb pieces facilitating sliding movement of said blade. The blade 23 also has an elongated aperture 31, the side walls of the forward end of which has inwardly extending cleats 32 which form keys for guiding a sliding key block 33 with respect to the blade 23. The upper portion of the block 33 is of such width as to pass freely but snugly through the aperture 31 when the forward end of the block clears the cleats or flanges 32. Opposite sides of the block 33 are grooved as seen at 34 to receive the cleats or flanges 32 when the block 33 is moved forward.

The lower portion of the block 33 is also provided with outwardly projecting flanges 35 which extend beyond the side walls of the aperture 31. Thus the block 33 is keyed against tilting movement on the blade 23 when in a position similar to that shown in Fig. 2 of the drawing. The purpose of this construction is to facilitate the handling of the blades in the assemblage thereof, while at the same time making it possible to detach the key block 33 from the blade 23 upon removal of an operating lever 36 from said block. The lever 36 has a yoked end 37 spanning an upward extension on the block 33 and is pivoted thereto by a screw 38. To the lever 36 is pivoted as seen at 39 an internally threaded arm 40 adjustably supporting a rod 41 terminating at 70 its free end in a wide plate 42 having laterally extending pivot pins 43 adapted to be placed in the bayonet apertures 13 in pivotally coupling the rod 41 with the plates 12. The coupling between the arm 40 and rod 41 provides relative

adjustment of the pivots 39 and 43 in changing the location of the block 33 as will be apparent.

It will be understood that the rear portion of the aperture 31, or in other words, that portion 5 thereof rearwardly of the cleats or flanges 32, will be of a length equal to or slightly greater than the length of the block 33 to facilitate the passage of the block 33 upwardly through the aperture 31. However, in the normal position 10 of the block with respect to the blade 23, it will assume a position wherein the cleats or flanges 32 are in engagement with the grooves 34 of said block. The lever 36 is of course coupled with the block after it has been arranged in the aperture 31. The yoked end of the lever 36 prevents the rear end of the block 33 from dropping through the aperture. With this construction the lower end of the block including the flanges 35 are maintained in substantially parallel relationship to the lower surface of the blade 23 at 15 all times. This enlarged end forms a keyway snugly but freely fitting within apertures 44 and 45 formed in the blades 24 and 25 respectively, thus maintaining alinement of the rear end portions of all of the blades while at the same time placing the blade 25 in direct operative engagement with the block 33 to facilitate manipulation of the blade or knife 25 by the lever 36. In other words, the length of the aperture 45 is such as to freely receive the lower portion of the block 33, and by swinging the lever 36 to the right from the position shown in Fig. 2, the blade will be moved forwardly in the direction of the end 18 of the ring 16, whereas movement of the lever 20 into the position shown in Fig. 2, withdraws the blade from the outer end of the ring.

The inner end portion of the blade 24 has laterally extending wings 46 which form thumb or finger pieces facilitating manual movement of the blade 24 and the support of this blade in operative positions. Beyond the wings 46, the blade has a protruding reduced extension 47 which is adapted to pass through the yoked end 29 of the blade 23 so that in the use of the instrument, the nut 27 will operate upon the extension 47 to advance the blade 24 to a point where the end of the extension 47 is flush with the end of the yoke 29. At this point both blades 23, 24 may be simultaneously moved forward to apply an equalized pressure upon the tissue, thus preventing uneven or unbalanced application of pressures by these blades and preventing severance or cutting of the tissue by the rounded ends of these blades which seat upon the rounded surfaces 48 of the ring 16 above and below the groove 17. The thicknesses of the blade edges are equal to the thicknesses of the surfaces 48 at the outer end portion 18 of the ring so that these blades present smooth upper and lower surfaces at the end portion 18 of the ring. It will be understood that the application of equalized pressure on the blades 23, 24 operates in a manner that one blade checks the forward progress of the other, and a physician will soon realize the amount of pressure required upon the nut 23 to insure a firm engagement with the tissue without danger of severing the tissue and yet insuring the firm support of the tissue between the blade edges and the surfaces 48.

The length of the aperture 44 in the blade 24 is such as to provide free movement of the block 33 therein so that in the rearward or withdrawal movement of the blade, no movement is applied to the blade 24, thereby assuring the gripping of

the severed tonsil in the instrument in the manner illustrated in Fig. 6 of the drawing.

The blade 25 is shorter than both of the blades 23 and 24, and the forward wide end thereof terminates in a pointed or prong-like end 25a centrally of the blade. The blade is beveled on both upper and lower surfaces in sharpening or grinding the same, as will appear in Figs. 3 to 6, inclusive, and these sharpened ends extend to the side edges of the blade so as to insure the cutting of all of the tissue engaged between the ends of the blades 23, 24 and the outer end portion 18 of the ring 16. In the forward movement of the knife or blade 25, the pronged end 25a thereof will extend into the aperture 20, but not sufficiently to protrude beyond the outer end of the ring.

In the use of the instrument, all of the blades will be drawn backwardly substantially into the position shown in Fig. 2 to expose the ring 16. With the tool in this position, the ring end of the instrument is inserted into the throat and the tonsil is passed through the ring in the usual manner. When held in this position, the thumb of the hand is applied to one of the wings 30 to advance the blade 23 manually in the direction of the end of the ring to engage the tissue in the manner illustrated in Fig. 3 of the drawing. In this position of the parts, the extension 47 will be protruding through the yoke end 29 and the physician now spins the nut 27, moving the same in the direction of the extension 47, and continues to turn this nut until the extension 47 has moved to a position flush with the end of the yoke 29. Then the nut is turned slightly to apply sufficient pressure to firmly engage the tissue between both blades 23, 24 and the end 18 of the ring, in the manner clearly seen in Fig. 4 of the drawing. In this position, the tissue is supported firmly between the ends of the blades 23, 24, and is securely and positively held in this position, eliminating any further care or attention on the part of the physician and preventing any possible loosening of the tissue which has been experienced by slackening manual pressure upon the blades as heretofore experienced.

The physician then moves the lever 36 rearwardly which advances the knife or blade 25 forwardly, and the pointed or pronged end 25a will first pierce or puncture the firmly supported tissue and then pass through the tissue in shear-like action, producing a clean cutting or severing of the firmly supported tissue. After this, the thumb of the hand supporting the instrument is moved into engagement with one of the wings 46 to apply slight pressure thereon. Thereafter, the nut 27 is loosened to free the blade 23, the lever 36 is then moved forwardly to withdraw the blade 25, and the blade 23 is moved rearwardly out of engagement with the ring end 18, thus freeing the tissue adjacent the throat. The instrument may then be removed and will have the removed or severed tonsil supported in connection with it by the blade 24, upon which the slight manual pressure has been applied by engagement of one of the wings 46. The purpose of this latter engagement is to avoid opening movement of the blade 24 by its frictional engagement with the blade 25, but very slight pressure will be required to resist this frictional engagement.

It will of course be understood that when the instrument has been removed from the patient's throat, the tonsil may be dropped from the instrument by simply manually sliding the blade

24 rearwardly. In order to insure the application of synchronized pressure of the blades 23, 24 upon the tissue engaged thereby, it is essential that the length of these two blades with respect to the forward rounded ends thereof and the inner surface of the yoke 29 and the end of the extension 47 be the same; that is to say, assuming that the two surfaces 48 engaged by the blades are in common vertical alinement.

10 In the above described cycle of operation and in moving the lever 36 forwardly to withdraw the knife, the block 33 may engage the blade 23 to move the same rearwardly to a slight extent. This movement is of course not objectionable, and in fact would be desirable in that it will eliminate the separate operation of manually retracting the blade 23. It is desirable to provide sufficient clearance in the length of the aperture 44 to prevent the aforesaid movement of the block 33 from contributing any movement to the blade 24, the result of which would free the tonsil from the instrument before the instrument has been removed from the throat.

In assembling and disassembling the parts, it will be apparent that the screw 27 is moved into a position adjacent the stop nut 28. The three blades 23, 24 and 25 arranged one upon the other in the manner illustrated are then placed upon the top of the body rearwardly of the enlargement and between the plates 12, and are then moved forwardly. The pin 41 is then coupled with the plates 12 and the lock or retaining plate 14 is moved into operative position. To detach the parts, the above operation is reversed.

25 By reason of the simplicity of the construction, it is only a matter of a few seconds to assemble and disassemble the parts. In this way, cleaning or the sterilization of the instrument may be effected, thus maintaining long life and durability of the instrument.

The blade or knife 25 is of one thickness and balanced contour and may be inserted in position with either side of the blade upward, by reason of the double grinding of the cutter edge thereof.

Having fully described my invention, what I claim as new and desire to secure by Letters Patent, is:

1. In a tonsillotome of the class described, an elongated body portion terminating at one end in a thin ring grooved and recessed on its inner surface, two tissue engaging blades slidably mounted on said body and having rounded ends movable toward and from the inner surface of said ring to engage tissue above and below the grooved and recessed portion of the ring, a knife arranged between said blades and having a sharpened end movable into the grooved and recessed portion of said ring, said sharpened end of the knife being pointed centrally whereby the tissue supported between said blades will be first pierced by said pointed end in advancing the knife in the direction of said grooved ring, said blades and said knife all having vertically alined apertures in the shank portions thereof, a key block arranged in said apertures, means on said block and on the apertured portion of one of said blades for keying said blades and knife in coupled relationship, means on said block and one of said blades for retaining the blade against accidental displacement from said block, and a lever pivotally coupled with said body and with said block for moving the block longitudinally of said body in advancing and retracting said knife.

2. In a tonsillotome of the class described, an elongated body portion terminating at one end

in a thin ring grooved and recessed on its inner surface, two tissue engaging blades slidably mounted on said body and having rounded ends movable toward and from the inner surface of said ring to engage tissue above and below the grooved and recessed portion of the ring, a knife arranged between said blades and having a sharpened end movable into the grooved and recessed portion of said ring, said sharpened end of the knife being pointed centrally whereby the tissue supported between said blades will be first pierced by said pointed end in advancing the knife in the direction of said grooved ring, said blades and said knife all having vertically alined apertures in the shank portions thereof, a key block arranged in said apertures, means on said block and on the apertured portion of one of said blades for keying said blades and knife in coupled relationship, means on said block and one of said blades for retaining the blade against accidental displacement from said block, a lever pivotally coupled with said body and with said block for moving the block longitudinally of said body in advancing and retracting said knife, and means in threaded engagement with said body for simultaneously advancing both of said blades in the direction of said ring independent of said knife.

3. An instrument of the class described comprising an elongated body, the outer end of said body terminating in a relatively thin ring, three elongated blades disposed one upon the other on said body and independently movable longitudinally thereof, the upper and lower blades comprising tissue engaging members cooperating with said ring, the intermediate blade comprising a knife adapted for severing the tissue engaged by said members, said blades having registering elongated apertures at end portions thereof remote from said ring, a longitudinally movable key block extending through said apertures maintaining the alinement of said blades, means movable longitudinally of said body for uniformly supporting said members in tissue engaging position, and said key block closely engaging the aperture of said knife blade thereby forming means for positively supporting and moving said knife blade independently of said members.

4. An instrument of the class described comprising an elongated body, the outer end of said body terminating in a relatively thin ring, three elongated blades disposed one upon the other on said body and independently movable longitudinally thereof, the upper and lower blades comprising tissue engaging members cooperating with

said ring, the intermediate blade comprising a knife adapted for severing the tissue engaged by said members, said blades having registering elongated apertures at end portions thereof remote from said ring, a longitudinally movable key block extending through said apertures maintaining the alinement of said blades, means movable longitudinally of said body for uniformly supporting said members in tissue engaging position, said key block closely engaging the aperture of said knife blade thereby forming means for positively supporting and moving said knife blade independently of said members, and means pivoted to said block and linked to said body forming an actuating lever for said knife blade.

5. In an instrument of the class described comprising an elongated body terminating at one end in a relatively thin ring, three superimposed blades independently movable toward and from said ring, the top and bottom blades forming means for clamping tissue against said ring, the intermediate blade comprising a knife adapted to sever the tissue between said first named blades, independent means for moving said blades, a key member movable longitudinally of said body, cooperating means on said key member and blades for maintaining vertical alinement of said blades, and said key member slidably engaging said top and bottom blades and closely engaging said intermediate knife blade thereby forming means for positively advancing and retracting said knife blade with respect to the top and bottom blades.

6. In an instrument of the class described comprising an elongated body terminating at one end in a relatively thin ring, three superimposed blades independently movable toward and from said ring, the top and bottom blades forming means for clamping tissue against said ring, the intermediate blade comprising a knife adapted to sever the tissue between said first named blades, independent means for moving said blades, a key member movable longitudinally of said body, cooperating means on said key member and blades for maintaining vertical alinement of said blades, said key member slidably engaging said top and bottom blades and closely engaging said intermediate knife blade thereby forming means for positively advancing and retracting said knife blade with respect to the top and bottom blades, and other means movable longitudinally of said body for uniformly supporting said top and bottom blades in clamping position.
